Inventor

Mary J. Delmage,
By her Attorney,
Dr. C. L. Shaw & Co.

UNITED STATES PATENT OFFICE.

MARY JANE DELMAGE, OF NORTH BILLERICA, MASSACHUSETTS.

FRUIT-STRAINER.

SPECIFICATION forming part of Letters Patent No. 423,597, dated March 18, 1890.

Application filed November 1, 1889. Serial No. 328,886. (No model.)

To all whom it may concern:

Be it known that I, MARY JANE DELMAGE, of North Billerica, in the county of Middlesex, State of Massachusetts, have invented 5 certain new and useful Improvements in Fruit-Strainers, of which the following is a description sufficiently full, clear, and exact to enable any person skilled in the art or science to which said invention appertains 10 to make and use the same, reference being had to the accompanying drawings, forming part of this specification, in which—

Figure 1 is an elevation showing my improvement in use; Fig. 2, a top plan view of 15 the strainer, and Fig. 3 a plan view of the compressor.

Like letters and figures of reference indicate corresponding parts in the different figures of the drawings.

20 My invention relates especially to a device for straining cooked fruit during the process of making jelly; and it consists in certain novel features hereinafter fully set forth and claimed, the object being to produce a simpler, cheaper, and more effective device of 25 this character than is now in ordinary use.

The nature and operation of the improvement will be readily understood by all conversant with such matters from the following 30 explanation.

In the drawings, A represents the bag, which is constructed of cloth sufficiently porous to permit the fruit-juice to be forced therethrough. A metallic ring b is secured 35 in the mouth of the bag, said ring being grooved peripherally. A loop or eye d is formed on said ring at opposite sides thereof. A holder B, consisting of a single piece of wire coiled at f to form a spring, has its arms 40 g h bent or curved at i on the same circle as the hoop or ring b. The arms g h of the holder are passed through the eyes d of the ring b until their curved portions i enter the ring-groove, the spring end f of said holder 45 clamping said arms tightly against the ring. The holder serves as a handle for manipulating the device when the bag is filled with the hot fruit, and also as a support whereby the bag may be suspended in the mouth of a 50 utensil for receiving the fruit-juice.

The compressor D consists of a single rod of wire coiled at p to form a spring, the outer ends of the arm q r being curved at v on an arc of the same circle as the ring b, and adapted to be passed through the eyes d into 55 the groove of said ring when not in use, in the same manner as the holder B.

The bag being filled with the cooked fruit is suspended over a receptacle adapted to receive the juice. The bag is then encircled 60 by the curved arms of the compressor, as shown in Fig. 1, which are forced together and drawn gradually downward over said bag. This expels the fruit-juice through the cloth without injuring the hands of the operator, 65 in a manner readily understood by all conversant with such matters without a more explicit description.

Having thus explained my invention, what I claim is—

1. In a fruit-strainer, a bag, a grooved ring in the mouth thereof, loops at opposite sides of said ring, a detachable wire-holder coiled to form a spring and bent to partially encircle said ring, substantially as described. 70

2. In a fruit-strainer, a bag provided with a grooved ring in its mouth, a holder comprising a wire rod coiled to form a spring and having its ends curved to partially encircle the ring, and a spring-compressor, substantially as described. 75

3. In a fruit-strainer, the bag A, ring b, and spring-holder B, in combination with the compressor D, having the spring p and curved ends v, substantially as described. 85

4. In a fruit-strainer, a bag, a grooved ring in the mouth thereof, loops on said ring, a holder bent to form a torsion-spring at one end and having its body curved to partially encircle the ring, and a compressor comprising a wire rod coiled at one end, its opposite ends being curved substantially as and for the purpose set forth. 90

MARY JANE DELMAGE.
